FUSE INDICATOR

Frank C. La Mar, New York, N. Y.

Application August 25, 1933, Serial No. 686,673

3 Claims. (Cl. 200—121)

This invention relates to electrical fuses, especially to electrical fuses of the cartridge type, and more particularly to an indicator for such fuses which acts to give information as to the integrity of the fusible element.

It is well understood by those skilled in the electrical art that safety requires all circuits which carry or are capable of carrying an appreciable amount of current must have safety devices inserted in them to prevent an excessive flow of current under abnormal conditions.

A common safety device is the well known fuse made of a strip of metal which will melt upon the flow therethrough of an undesirable heavy current.

Fuses are made of many forms amongst which is the cartridge fuse which may be either of the ferrule type or the knife blade type.

In either case it is convenient and desirable to have means of simple form by which the fact that the fusible metal has melted may be indicated without removing the fuse from its position and disassembling it.

Integrity indicator means have been devised for application to both the ferrule type and the knife blade type of fuse, but these indicators are of a form which does not insure a positive and unfailing retention in position upon the fuse where extreme vibration occurs.

A principal object of applicant's invention is the provision of an indicator applicable particularly to fuses of the knife blade type by which the integrity of the fusible element of the fuse may be ascertained by a visual inspection without disassembling the fuse or disturbing the position thereof, and which will be of such a form that no vibration, however extreme, will cause the indicator to become separated from the fuse.

Other objects and advantages will appear as the description of the particular physical embodiment selected to illustrate the invention progresses, and the novel features of the invention will be particularly pointed out in the appended claims.

In describing the invention in detail and the particular physical embodiment selected to illustrate the invention, reference will be had to the accompanying drawing, and the several views thereof, wherein like characters of reference designate corresponding parts throughout the several views, and in which:

Figure 1 is a side elevational view of a conventional knife blade cartridge fuse in place in the usual and conventional clips with an indicator embodying applicant's invention shown there-

with; Fig. 2 is a cross-sectional view of the device as shown by Fig. 1 on the plane indicated by the line II—II of Fig. 1, viewed in the direction of the arrows at the ends of the line; Fig. 3 is a perspective view of applicant's indicator.

5

Numerals 1 designates an ordinary and conventional mounting panel upon which are the ordinary and well known binding bolts 2 and 3, for attaching the conducting wires 4 and 5 of a circuit in which a fuse is to be inserted. Bolts 2 and 3 10 are connected by means of metallic strips 6 and 7 to the usual fuse clips 8 and 9.

A usual and conventional form of knife blade cartridge fuse 10, having blades 11 and 12, and metallic caps 13 and 14, and metallic ferrules 15 15 and 16, is positioned connecting the clips 8 and 9.

In order to visually indicate the integrity of the thermal element of the fuse 10, applicant provides an indicator which embodies a lamp 17. This lamp 17, in accordance with applicant's invention, is connected between the knife blades 11 and 12. When the thermal element of a fuse 10 is intact the lamp exhibits no glow but when the thermal element of the fuse 10 has been destroyed the lamp 17 becomes illuminated.

25

Applicant provides a metallic arm 18 formed with a slot 19. This slot 19, as best shown in Fig. 2, is adapted to embrace a blade of the fuse. It is also of a thickness such that it may well be positioned between a cap as 13 and a clip as 8. 30 When the arm 18 is in the position as shown by Fig. 1, it is impossible to remove the arm from the fuse without first removing the fuse from the clip.

35

For making electrical connection to the other fuse blade applicant prefers a metallic spring clasp 21, best shown in Fig. 3. This metallic spring clasp may be readily pushed on to the cap 14 or removed therefrom.

Between the arm 18 and the spring clasp 21 40 applicant preferably provides a supporting covering and protecting insulating tube 22. This tube is connected at one end to the arm 18 and at the other end to the spring clasp 21 in any suitable and appropriate manner. Applicant 45 prefers to employ metallic bushings 23 and prefers to rigidly attach the bushings to the tube 22 by means of rivets as 24 and to then rivet as by rivets 25 the arm 18 and the spring clasp 21 to the bushings 23.

50

The lamp 17 is preferably of the glow type having two electrodes therein, 26 and 33, and having two terminals 27 and 28. One of the terminals 27 is electrically connected to the arm 18. The other terminal 28 is connected to a 55

leak resistance 29 and by means of a conductor 30 to the spring clasp 21.

The connection of terminal 27 to arm 18 and conductor 30 to spring clasp 21 is preferably effectuated by means of eyelets, as 31, which pass through the arm and spring clasp and are upset at each end. After the eyelets 31 are upset, the terminal 27 and the conductor 30 are securely held in place by a drop of solder 10 as 32.

From the above description it will be readily seen that the indicator of applicant's invention is of a form such that it may be placed in position upon a knife blade cartridge fuse with great facility before that cartridge fuse is placed in clips, but after the cartridge fuse is placed in clips it is impossible to remove the indicator, so that vibration, no matter how severe, would not cause the indicator to become separated from the fuse.

Although I have particularly described one particular physical embodiment of my invention, and the principle and construction thereof, nevertheless, I desire to have it understood that the form selected is merely illustrative but does not exhaust the possible physical embodiments of the idea of means underlying my invention.

What I claim as new and desire to secure by Letters Patent of the United States, is:

1. In an integrity device for a cartridge fuse, in combination: a metallic arm formed with a slot adapted to receive a fuse blade and be positioned between a cap of a fuse and a fuse clip

whereby the arm cannot be removed except when the fuse blade is out of the clip; an electrical indicator having two terminals, one of the terminals electrically connected to the said arm; and means for electrically connecting the other terminal to the other fuse blade.

2. In an indicator, for a cartridge fuse of the type having a blade on each end and a cap surrounding the blade adapted to be held in fuse clips, in combination: a metallic arm formed with a slot adapted to receive a fuse blade and be positioned between a cap and a clip whereby the arm cannot be removed from the blade without first removing the fuse blade from the clip; an electrical indicator having two terminals; means for electrically connecting one of the terminals to the arm; a metallic spring clasp adapted to embrace the cap on the end of the fuse remote from the arm; and means for electrically connecting the other terminal of the indicator to the metallic clasp.

3. In an indicator for a cartridge fuse, in combination: a metallic arm formed with a slot adapted to receive a fuse blade and be positioned between a cap of a fuse and a fuse clip whereby the arm cannot be removed from the blade without first removing the fuse blade from the clip; an indicator lamp forming electrical connection with the arm and supported thereby; and means also connecting the lamp electrically with the other blade of the fuse.

FRANK C. LA MAR.
